UNITED STATES PATENT OFFICE.

HERBERT S. BROWN, OF NEW YORK, N. Y.

SWITCH FOR ELECTRIC CIRCUITS.

No. 861,800.

Specification of Letters Patent.

Patented July 30, 1907.

Application filed May 12, 1906. Serial No. 316,442.

To all whom it may concern:

Be it known that I, HERBERT S. BROWN, a citizen of the United States, and a resident of the city of New York, county and State of New York, have invented 5 certain new and useful Improvements in Switches for Electric Circuits, of which the following is a specification.

This invention relates to switches, such as are used for connecting an incandescent lamp with the circuit 10 from which it is supplied or for connecting sections of lighting or power circuits.

The object of the invention is to provide a circuit closing device having a single push button movement so arranged that successive depressions of the button 15 close and open the circuit; a further object of the invention is to improve and cheapen the mechanical construction of such switches.

In the accompanying drawings Figures 1 to 8 inclusive, illustrate the invention in its preferred form applied as a socket switch. Fig. 1 is a sectional side view of a socket with the casing partly broken away; Fig. 2 is a view from the rear side of Fig. 1 with the casing removed; Fig. 3 is a section on line *c*, *d*, Fig. 1; Fig. 4 is a plan view on line *a*, *b*, Fig. 1; Fig. 5 is a sectional plan view to show the switch contacts in an intermediate position; Fig. 6 is a section on line *g*, *h*, Fig. 4, showing the push button and flexible finger; Fig. 7 shows details of construction of the push button and switch; Fig. 8 shows the supporting post and 25 spring holder for one of the movable circuit terminals of the switch; Figs. 9 and 10 show a modified form of switch applicable as a socket, pendant, or similar form of switch; and Figs. 11 and 12 show a second modification in the form of the switch.

The socket, Figs. 1 to 8 inclusive, consists of a base 35 piece 20 of insulating material to which are fixed two circuit terminals, one of which 21 is a screw terminal; the other or central terminal 22 is a flat, spring-like contact. Beneath the free end of the terminal 22 is a 40 post or pillar 23 formed integral with the base 20, and which supports the free terminal of the contact 22 against too vigorous pressure when the translating device is screwed into position. The terminal 22 is connected to the insulated conductor *w* and the terminal 45 21 is connected to the insulated conductor *v*, circuit passing through the switch to be described and the screw 24, shown in dotted outline in Fig. 1. The terminal 22 is preferably formed of spring brass and is held in position on the base 20 by means of a screw 25; 50 formed integral with this terminal 22 is a lug 26, and there is a screw 27 under which the bared terminal of the wire *w* is passed. When the screw is turned the friction tends to carry the wire away from the center of the screw, the wire sliding on the surface of the contact 22 and this lug 26 blocks and holds such movement without interfering with the ready application

of the bared terminal of the wire *w* to its position under the clamp 27. More than one lug 26 is a disadvantage because it impedes and blocks the ready application of the bared wire terminal around the screw in apparatus where the parts are closely confined by a case or shell. This lug 26 is located on the left hand side of a right hand screw so that the movement of the screw carries the conductor against the lug.

28 is a circular shell of insulating material and 29 is 60 a metal shell which incloses the entire apparatus fitting closely upon the circular bottom of the base 20 over which a supplemental part 30 of the inclosing shell also fits. There is a single retaining screw 31 shown in dotted outline in Figs. 4 and 5, this screw passes 70 through an aperture in the bottom of the base 20 and through the shell 29, 30, at separated circumferential points 32 and 33. The nut 34 is inserted in the base 20 and blocked in position by cement 35; this nut is inserted through a lateral aperture 36 bored into the 75 base 20 from the side or vertical surface of said base.

The switch or circuit breaker forming part of the socket is composed of two movable, spring-retracted interlocking circuit terminals; a yielding actuating finger is caused to engage first one terminal and then the 80 other to make and break the conducting contact between them; this finger is preferably flexible or flexibly supported and the terminals are resilient and interlock. The actuating device is preferably moved first to make and then to break circuit by a straight line, reciprocating movement characteristic of the ordinary push button. The simplest form of this switch is shown in Figs. 9 and 10; 20 is the insulating base of the socket; a blade spring of conducting material, like 85 spring brass, is anchored at 47; this spring 40 has a hook 90 terminal 41, the other circuit terminal 42 is of similar material and is anchored at 48. 45 is a retracting push button fixed to the bar 47 reciprocating in the guides 49. 46 is a retracting-spring holding the push button 45 in the position shown. Fixed to this push button is 95 a flexible finger 43 having a terminal 50 fixed at an angle with respect to the blade or spring 43. When the push button 45 is depressed, it being normally in the position shown in Fig. 9, terminal 50 engages blade 42 which makes contact with blade 40, and the deflection given to both causes the free end of blade 44 to pass the point of the spring 41 and blade 44 becomes interlocked behind the point of the hook 41, this closes the circuit. The next time the button 45 is depressed it engages the hook 41 and the resulting deflection tends to straighten 105 out both springs, thus releasing spring 42 which snaps away and breaks the circuit. Upon the release of the button 45 the parts return to the position shown in Fig. 9. The form of this switch as it appears in Figs. 1 to 7 inclusive embodies the same principle of construction 110 and operation but the parts are more substantial and occupy more space in the socket; in these seven figures,

40 and 42 are the electrical contact points of substantially similar construction, the moving contact 40 moves on a pin 60 formed of a block of metal 61, and there is an adjacent shoulder 62 to receive the spring 63, which is formed into a loop at 64 and when forced down between the shoulder 62 and the block 61, one of its ends is in position to engage with the free end of the electrical contact 40, and the other end engages a "flat" on the side of contact 40, tending to keep contact 40 always in a fixed position. The second contact 42 moves on a similar pin 70. The spring 73 is formed as shown in Fig. 3 and is bent to closely surround the metal base piece forming part of post 70 with which base piece it makes frictional engagement, and is retained in such position by the adjacent insulating base, by this arrangement no rivets or fastening devices are required to hold the spring in position. In a plane below the contact 42 and affixed thereto is a hooked arm 71, and in the same plane, fast on the contact 40 is a hooked arm 72. The free ends of the arms 71 and 72, and the free ends of the electrical contacts 40 and 42 are in position to interlock, to make and break electrical contact and the parts 40 and 42 are in the same plane, which is parallel to the plane in which the arms 71 and 72 are located; the contact 40 and the arm 72 are movable on the pin 60 and the contact 42 and the arm 71 are movable on the pin 70. 73 is a flat spring having one end fixed in position and its free end engages the free end of the arm 71. The flexible finger 43 is fixed to the push button 45. This push button is in a sleeve 80 and the sleeve is held in position by cement 96. The spring 46 abuts at one end against the insulating base 20, and at the other end spring 46 abuts against a tubular section in which the push button 45 is fixed, and which surrounds the finger 43. In its normal position the push button is as shown in Fig. 4, where the contacts 40 and 42 are shown to have completed the electrical circuit. In Fig. 7, the normally open position is shown, where the contact 40 is separated from the contact 42. These two positions are attained by successive depressions of the button 45. Assuming the switch is in the normally open circuit position, shown in Fig. 7, when the button 45 is depressed the flexible finger 43 engages lever 71 and depresses it against the force of the spring 73; arm 71 in its movement rotates on the pin 70 carrying contact 42 into engagement with contact 40, which yields, allowing the point of contact 42 to pass and take a position between the end of spring 63 and contact 40; upon releasing button 45, spring 73 forces contact 42 to ride upon the end of contact 40 and circuit remains closed between 40 and 42, and the parts come to rest in the position shown in Fig. 4. The next depression of button 45, the parts being as shown in Fig. 4, flexible finger 43 engages arm 72 and the parts take the position shown in Fig. 7. It will be noticed that the parts 71 and 42 movable on the pin 70, and the parts 72 and 40 movable on

the pin 60 constitute two movable, spring-retracted, interlocking circuit terminals.

A modification of this switch is shown in Figs. 11, 12. The circuit terminals 40 and 42 are like those represented in Fig. 9, and are duplicated to form a double pole switch. The yielding actuating device 43 is modified to operate both switch contacts simultaneously, extensions 90 and 91 being attached to it for this purpose. The flexible finger 43 is supported on a spring 93 and the push button 45 on the rod 47 has a retracting spring 46, all as heretofore described. The rod 47 on which the push button is located passes through an elongated aperture 92 in the actuator 43. This actuator 43 is capable of movement in two directions simultaneously, that is, it is yielding and flexible. It is intended that this modification of the switch shall be used in connection with circuits of greater amperage, and in positions where the actuator must have considerable strength combined with limited dimensions in the direction of the movement of the push button.

What I claim and desire to secure by Letters Patent is:

1. The combination in an electric switch of two movable spring-retracted interlocking circuit terminals, a yielding actuating finger therefor and means whereby said finger is caused to engage first one terminal and then the other to make and break conducting contact.
2. The combination in a switch of two interlocking spring retracted contacts, and means for causing said contacts to engage and disengage consisting of a yielding spring retracted device, and an independent actuator therefor.
3. The combination in a switch of two interlocking spring retracted contacts and means for causing said contacts to engage and disengage consisting of a yielding actuating device, and a controlling device moving in a straight line.
4. In an electric switch the combination of two movable interlocking spring retracted contacts and a flexible, spring retracted actuating device therefor.
5. In an electric switch the combination of two interlocking spring retracted contacts, a flexible, spring-retracted actuating device therefor and a push button for moving said device.
6. In an electric switch a yielding spring-retracted actuating device combined with two resilient contact terminals and means whereby said terminals interlock.
7. In an electric switch a yielding, spring-retracted, actuating device combined with two resilient contact terminals, means whereby said terminals are caused to interlock, and means whereby said actuating device is caused to engage first one terminal and then the other.
8. In an electric switch the combination, with a movable spring-retracted contact and a complementary contact, of a yielding, spring-retracted actuating device therefor.
9. In an electric switch a yielding spring-retracted actuating device combined with a resilient contact, a complementary contact and means whereby said contacts are caused to interlock.
